UNITED STATES PATENT OFFICE

110,736

DESIGN FOR A COMBINED DIAL AND HANDS FOR A CLOCK OR SIMILAR ARTICLE

William W. Scotten, Terre Haute, Ind.

Application May 17, 1938, Serial No. 77,255

Term of patent 14 years

To all whom it may concern:

Be it known that I, William W. Scotten, a citizen of the United States, residing at Terra Haute, in the county of Vigo and State of Indiana, have invented a new, original, and ornamental Design for a Combined Dial and Hands for a Clock or Similar Article, of which the following is a specification, reference being had to the accompanying drawing, forming part thereof.

Figure 1 is a plan view and Figure 2 an edge view of a combined dial and hands for a clock dial or similar article showing my new design,

the principal characteristic features of which reside in the dial being divided into two equal series of spaces numbered from one to twelve, the representation of the sun in the center of the dial, and the representation of the earth on the end of the hour hand, whereby the relative positions of the sun and earth are visible.

I claim:

The ornamental design for a combined dial and hands for a clock or similar article, substantially as shown and described.

WILLIAM W. SCOTTEN.
